(57) **CLAIM**

The ornamental design for a push to dispense valve for a beverage dispensing machine, as shown and described.

DESCRIPTION

FIG. 1 is a perspective view of a push to dispense valve for a beverage dispensing machine, showing our new design;
FIG. 2 is a front view thereof;
FIG. 3 is a first side view thereof;
FIG. 4 is a second side view thereof;
FIG. 5 is a top view thereof; and,
FIG. 6 is a bottom view thereof.

The broken lines in the figures illustrate the portions of the design that form no part of the claimed design.

1 Claim, 5 Drawing Sheets
